CLAIM

The ornamental design for a shroud for a floor-engaging bolt mounted at the bottom of a panic-bar latch equipped door, as shown and described.

DESCRIPTION

FIG. 1 is a front perspective view of a shroud for a floor-engaging bolt mounted at the bottom of a panic-bar latch equipped door showing our new design; FIG. 2 is a top plan view thereof, the undisclosed bottom plan view being a mirror image thereof; FIG. 3 is a front elevation view thereof; FIG. 4 is a right side elevational view thereof; FIG. 5 is a rear elevational view thereof; and, FIG. 6 is a left side elevational view thereof.
